UNITED STATES PATENT OFFICE.

JOHN C. A. ANDERSON, OF CHICAGO, ILLINOIS.

SAFETY CONTROL SYSTEM.

1,168,586.

Specification of Letters Patent.

Patented Jan. 18, 1916.

Application filed November 24, 1913. Serial No. 802,843.

To all whom it may concern:

Be it known that I, JOHN C. A. ANDERSON, a citizen of the United States, residing at Chicago, in the county of Cook and State 5 of Illinois, have invented a certain new and useful Improvement in Safety Control Systems, of which the following is a full, clear, concise, and exact description, reference being had to the accompanying drawings, 10 forming a part of this specification.

My invention relates to controlling devices and has for its object the provision of improved means for preventing the operation of elevators either passenger or 15 freight should the doors or other means for preventing access to the car or hatch not be in their access preventing position.

My invention is particularly adapted to the control of elevators by mechanically 20 controlling the operating devices, and broadly speaking my invention concerns itself with the provision of devices to control at predetermined times the operation of the starting lever or rope. In the form of the 25 invention as herein disclosed I provide means which when such doors are open will then lock the starting lever against operation, but will not entirely prevent the movement of this lever against this controlling action should it be necessary in an emergency or otherwise to operate the lever even 30 though the door were open.

In describing my invention and in the claims I will use the door as indicating any 35 access preventing means either provided upon the car of the elevator itself or upon the framework at each floor.

I will describe three forms which my invention may take more in detail by referring 40 to the accompanying drawing, in which—

Figure 1 is a diagrammatic view of a control system arranged in accordance with my invention; Fig. 2 is a partial view of the mechanism of Fig. 1 shown in an alternative 45 position; Fig. 3 is a similar diagrammatic view of a modification, and Fig. 4 is a fragmentary view of a modification.

Referring more particularly to Fig. 1, I show diagrammatically a floor 1 of an elevator car, in which car there is suitably provided a starting lever 2 adapted to con-

trol a cable 3, which cable of course extends to the starting and stopping devices for controlling the movement of the car. The lever 2 in this specific form is provided with an extending stud 4 carrying the two arms 5 and 6. These arms at their extremities are each provided with pins 7, 7, which are adapted to slide in slots 8, 8 provided respectively upon arms 9 and 10. These arms 60 9 and 10 are linked to the plunger 11 associated with a solenoid 12. This solenoid is preferably mounted within a suitable framework 13 and may desirably be attached to the underside of the floor 1. The 65 arrangement of the slots 8 is such that whenever the solenoid is attracted to the position shown in Fig. 1, that then the right hand extremities of each of the slots 8 engage the pins 7, 7.

Now whenever the lever 2 is actuated in either a clockwise or counterclockwise direction, then the particular pin 7 of which ever one of the arms 5 or 6 is moved away from the solenoid withdraws the plunger 11 70 into the dotted position shown in Fig. 1. Then if thereafter the solenoid should become energized the attraction of its core 11 will cause the particular arm 9 or 10 to rotate the lever 2 into its central or neutral 75 position shown by the full lines of Fig. 1. Now the solenoid 12 receives its current from any suitable source of supply, here shown as a generator 14, and the circuit through the generator and solenoid 12 is 80 controlled through the agency of suitable instrumentalities bridged to extending conductors 15 and 16. These conductors extend into proximity of each one of the doors 17, 18 and 19, it being of course desired that 85 each door which permits access to the car be also provided with controlling devices to prevent operation of the car should the particular door be open. Each car may be provided with a projection 20 adapted to 90 control circuit through springs 21 and 22. Normally when this projection is away from the springs as shown in the case of the door 17, then the circuit through the springs 21 and 22 is closed, thus closing the circuit 100 across the conductors 15 and 16, thereby completing a circuit through the solenoid

11, whereby to attract its core 11 and withdraw the hand lever 2 into its neutral position should the handle at that particular time be away from that particular position.

5 Now whenever the doors are closed as shown in the case of the doors 18 and 19, then the circuit through their springs 21 and 22 remains open and the solenoid 12 remains unenergized. It will thus be seen that 10 the solenoid always restores the handle 2 into its central position whenever any door is open, and thus would tend to hold it in that position, thus to prevent manipulation of the cable or movement of the car during 15 the time any such door is open. Of course it might happen during an emergency it would be desirable to operate the car despite the fact that a door is open. In that event, the handle 2 can be operated in opposition 20 to the pull of the core 11 and the degree of this pull can of course be regulated to any suitable extent as may be desired. For instance, it may be so regulated that it would 25 require the use of both hands to operate the lever under such conditions so as to be entirely sure that it would be only an emergency condition, which would permit such actuation against the action of the energized solenoid.

30 Referring more particularly to Fig. 3, I have provided the handle 2 with a brake pulley 23 which is associated with a suitable brake band 24. The brake band has an 35 extending arm 25 which is engaged by the spring 26 tending normally to force the brake band 24 into association with the brake pulley 23. Nut 27 is provided to hold the lower extremity of the spring 26. A solenoid 28 is provided which cooperates with a 40 plunger 29 associated with the arm 25. Now the arrangement in Fig. 2 is such that normally if the solenoid 28 is not energized, the handle 2 will be held in its last actuated 45 position by the brake band whenever a door is open. A suitable source of current supply 30 may be provided to furnish the current to the solenoid 28 and this circuit is connected through a series of springs 31 and 32 respectively, which springs are so arranged that each pair of springs is in series 50 with the circuit including the solenoid 28 and the source of current 30. Thus the circuit through all of the springs 31 and 32 must be closed before the circuit is established, and thus all of the doors must be closed before the solenoid 28 is actuated to 55 release the pressure of the brake band against the brake pulley 23. Each door 33 has a projection 34 to engage the springs and 60 close the circuit therethrough.

From this it will be seen that the pressure of the brake band against the brake pulley can be regulated to suit the requirements, irrespective of the strength of pull

of the solenoid 28. It will also be apparent 65 that the form shown in Fig. 3 is of such a character that it will be operable should the handle 2 normally be in a position slightly away from the vertical position, which it is intended to occupy when all of 70 the elevator devices are in their normal condition. It occurs sometimes that due to various leakage or other irregularities in the apparatus that the handle 2 when the car is at rest, may be in a position slightly away 75 from the vertical. It will be seen that the brake action would be just the same whichever is the neutral position of the handle 2.

80 In Fig. 4 I show a modification in which the starting cable 36 passes between a pair of jaws consisting of the fixed jaw 37 and the movable jaw 38. The movable jaw is controlled by a plunger 39 of a solenoid 40. Thus whenever the solenoid 40 is energized 85 the starting cable is gripped tightly, thus to prevent operation of the car unless extreme force is used.

90 From what has been described, the nature of my invention will be clear to those skilled in the art. It will also be clear that many modifications may be made without departing from the spirit of my said invention.

Having however thus described three forms which my invention may take, what 95 I claim as new and desire to secure by Letters Patent is:

1. A system of the character described comprising an elevator car, a control lever, an operating cable actuated by said control lever, a door for permitting access to said car, and means controlled by said door when in an open position to govern the actuation of said lever, said means including a solenoid, a plunger, a pair of arms associated with said lever, and a pair of links associating said arms with said plunger. 100 105

2. A system of the character described comprising an elevator car, a control lever, an operating cable actuated by said control lever, a door for permitting access to said car, and means controlled by said door when in an open position to retract said lever into neutral position, said means including a solenoid, a plunger, a pair of arms associated with said lever, and a pair of links associating said arms with said plunger. 110 115

3. A system of the character described comprising an elevator car, a control lever, an operating cable actuated by said control lever, a door for permitting access to said car, and means controlled by said door when in an open position to govern the actuation of said lever, said means including a solenoid, a plunger, a pair of arms associated with said lever, and a pair of links associating said arms with said plunger, there being lost motion between said links and said arms. 120 125

4. A system of the character described

- comprising an elevator car, a control lever, an operating cable actuated by said control lever, a door for permitting access to said car, and means controlled by said door when 5 in an open position to retract said lever into neutral position, said means including a solenoid, a plunger, a pair of arms associated with said lever, and a pair of links associating said arms with said plunger, there being 10 lost motion between said links and said arms.
5. A system of the character described comprising an elevator car, a control lever, an operating cable actuated by said control lever, a door for permitting access to said 15 car, and means controlled by said door when in an open position to govern the actuation of said lever, said means including a solenoid, a plunger, a pair of arms associated with said lever, and a pair of links associating 20 said arms with said plunger, there being lost motion between said links and said arms, said last means also including a switch associated with said door, and means movable with said door to control said switch.
- 25 6. A system of the character described comprising an elevator car, a control lever, an operating cable actuated by said control lever, a door for permitting access to said car, and means controlled by said door when 30 in an open position to retract said lever into neutral position, said means including a solenoid, a plunger, a pair of arms associated with said lever, and a pair of links associating 35 said arms with said plunger, there being lost motion between said links and said arms, said last means also including a switch associated with said door and means movable with said door to control said switch.
- 40 7. A system of the character described comprising an elevator car, a control lever, an operating cable actuated by said control lever, a door for permitting access to said car, and means controlled by said door when 45 in an open position to govern the actuation of said lever, said means including electromagnetic mechanism exerting a yielding restraint against the movement of said lever from its neutral position only during the 50 period of its actuated condition.
8. A system of the character described comprising an elevator car, a control lever, an operating cable actuated by said control lever, a door for permitting access to said car, and means controlled by said door when 55 in an open position to oppose the actuation of said lever, said means including electromagnetic mechanism exerting a yielding restraint against the movement of said lever from its neutral position only during the 60 period of its actuated condition.
9. A system of the character described comprising an elevator car, a control lever, an operating cable actuated by said control 65 lever, a door for permitting access to said car, and means controlled by said door when in an open position to retract said lever into neutral position, said means including electromagnetic mechanism exerting a yielding restraint against the movement of said lever from its neutral position only during the 70 period of its actuated condition.
10. A system of the character described comprising an elevator car, a control lever, an operating cable actuated by said control 75 lever, a door for permitting access to said car, and means controlled by said door when in an open position to govern the actuation of said lever, said means including restraining mechanism tending to restrain the movement of said lever from its neutral position, said restraining mechanism being operative only during the time said door is open.
11. A system of the character described comprising an elevator car, a control lever, an operating cable actuated by said control lever, a door for permitting access to said car, and electromagnetic means controlled by said door when in an open position to govern the actuation of said lever, said means including electromagnetic mechanism exerting a yielding restraint against the movement of said lever from its neutral position only during the period of its actuated condition. 85
12. A system of the character described comprising an elevator car, a control lever, an operating cable actuated by said control lever, a door for permitting access to said car, and means controlled by said door when 90 in an open position to govern the actuation of said lever, said means including restraining mechanism tending to restrain the movement of said lever from its neutral position, said restraining mechanism being operative only during the time said door is open and being instantaneously released upon closure of said door. 95
13. A system of the character described comprising an elevator car, a control lever, an operating cable actuated by said control lever, a door for permitting access to said car, and means controlled by said door when 100 in an open position to govern the actuation of said lever, said means including yielding restraining mechanism tending to restrain the movement of said lever from its neutral position, said restraining mechanism being operative only during the time said door is open and being instantaneously released upon closure of said door. 105
14. A system of the character described comprising an elevator car, a control lever, an operating cable actuated by said control lever, a door for permitting access to said car, and means controlled by said door when 110 in an open position to retract said lever into neutral position, said means including restraining mechanism to restrain the move- 115
- 120
- 125

ment of said lever from its neutral position, said restraining mechanism being operative only during the time said door is open and being instantaneously released upon closure 5 of said door.

In witness whereof, I hereunto subscribe

my name this 13th day of November, A. D., 1913.

JOHN C. A. ANDERSON.
